UNITED STATES PATENT OFFICE

LE ROY FLETCHER SNAPP, OF BROOKLYN, NEW YORK

SWIMMING APPLIANCE

Application filed February 23, 1927. Serial No. 170,161.

This invention relates to a swimming appliance and the principal object of the invention is to provide a swimming appliance which is simple in construction and which is 5 specially designed to be effective when the swimmer is using a swimming stroke on the order of the well known "crawl" stroke.

The device comprises a fin or blade arranged to be attached to the bottom of each 10 foot and constructed so that as the feet are moved up and down in the water the blades will have a very efficient propelling effect somewhat similar to that given by a fish's tail.

15 In order to give an understanding of the invention I have illustrated in the drawings a selected embodiment thereof which will now be described after which the novel features will be pointed out in the appended 20 claims.

Fig. 1 is a view of a swimmer equipped with my improved swimming appliance;

Figs. 2 and 3 are perspective views of a swimmer's foot having my improvement applied thereto, Figure 2 showing the position of the fin when the foot is moving upwardly 25 through the water and Fig. 3 when the foot is moving downwardly;

Fig. 4 is a view illustrating a modification 30 of the invention.

My improved swimming appliance comprises a fin or blade 1 which is constructed to be pivotally attached to the bottom of the foot 2 of a swimmer 3, the fin being attached 35 to the foot so that it can swing about an axis extending transversely of the foot. One convenient way of attaching the fin to the foot is by means of an attaching member 4 which is shaped to receive the heel portion 40 of the foot and is adapted to be strapped to the foot. The attaching member is of skeleton shape, it having two side portions 5 that extend along the sides of the foot at the ankle and which are connected both by the 45 back portion 6 that extends around the heel and by the bridge portion 7 which lies under the arch of the foot in front of the heel 8. This attaching member is shown as firmly strapped to the foot by means of an attaching strap 9 which is illustrated as extending

through slots or openings 10 formed in the sides of the member.

The blade or fin 1 is pivotally connected to the sides of the attaching member so that it can swing from the position shown in Fig. 2 to that shown in Fig. 3. Any suitable way of thus pivotally attaching the fin to the attaching member may be employed without departing from the invention.

In the construction shown in Figs. 1, 2 and 3 the fin is formed at its base with two arms 11 that are provided at their ends with trunnions 12 that are pivoted in apertures 14 formed in the sides 5 of the attaching member.

In order to make a satisfactory pivotal connection and one which will be comfortable for the swimmer I have formed each side 5 of the attaching member 4 with a slit 13 and have offset the metal between the slit and the aperture 14 through which the trunnion extends as shown at 15 so that the arm 11 may extend through the slit behind the offset portion 15, the end of the arm being bent outwardly to form the trunnion 12 which is journalled in the aperture 14. With this construction the slit 13 acts as a sort of guide for the arms 11 and the ends of the arms form stops which limit the swinging movement of the arm and the fin.

With the device attached to the feet as shown its use involves merely moving the legs and feet up and down in the water and preferably the feet will be moved up and down alternately as is usual in the crawl stroke. As the swimmer's foot is moved upwardly the fin will automatically assume the position shown in Fig. 2 it swinging down below the pivotal point and occupying the toe side of the foot.

The slit 13 is of such a length that when the fin is at the lower end of its movement it has an inclined position shown in Figs. 1 and 2 and as the foot is moved upwardly as shown by the arrows *a* the pressure of the fin in its inclined position against the water will have a very strong forward propelling force on the swimmer. When the foot approaches the surface of the water the swimmer will reverse the movement and swing the foot downward.

ly as shown by the arrows *b* in Figs. 1 and 3. As the foot is reversed the pressure of the water against the fin will reverse its position so that it will occupy a place opposite the heel portion of the foot. When the fin has been reversed and is at the limit of its upward position, as shown in Fig. 3, it still has an inclined position so that as the foot is moved downwardly it will give the swimmer a strong forward propelling force. The operation of the fin is thus somewhat similar to that of the tail of a fish when swimming and because of the arrangement shown there is no manipulation of the device required by the swimmer. All that is necessary is for the swimmer to move his feet up and down in the water and the swimming appliance will automatically function as above described. The action of this device may also be likened to that of 20 skulling a boat.

The fin may be made in various ways without departing from the invention. In Fig. 2, for instance, it is formed with a wire frame 16 of which the arms 11 form a part and this wire frame is covered with canvas or some other sheet material 17. I may also, if desired, provide the fin with a flexible extension 18 at its tip. This flexible extension will function to increase the propulsion during the reversing of the fin. As the fin is moved upwardly through the water the extension 18 will be bent backwardly by the pressure of the water. When the foot reaches the lower limit of its movement and begins to reverse the reversing movement will swing the fin downwardly into the position corresponding to that shown in Fig. 2 and as the fin is reversing the flexible extension 18 will also be reversed in position. This reversing of the 30 flexible extension will increase the propulsive effect of the fin.

In Fig. 4 I have illustrated a different embodiment of the invention wherein the fin, which is indicated at 20, has a relatively stiff intermediate portion and has a flexible portion 21 at the edge where it is fastened to the attaching member 4 and also has a flexible tip 22 which functions like the flexible extension 18 in Figs. 1, 2 and 3.

The fin shown in Fig. 4 may be secured to the attaching member in any suitable way. I have herein shown it as permanently secured to the bridge portion 7 of said attaching member, the portion 21 being sufficiently flexible to permit the fin to reverse and to swing from one operative position to the other.

It will thus be seen that while the invention is extremely simple in construction yet it is effective in operation as it adds very materially to the propelling force derived from moving the feet up and down in the water as is done in the crawl stroke.

While I have illustrated herein some selected embodiments of the invention I do not

wish to be limited to the constructional features shown.

I claim:

1. A swimming appliance comprising a fin and means for attaching the fin to the bottom of the foot of a swimmer to have a swinging movement below the bottom of the foot and about an axis extending transversely thereof, and means to limit the swinging movement so that in each extreme position said fin stands at an acute angle to the plane of the bottom of the foot, said fin in one extreme position forming an acute angle with the heel portion of the foot and in the other extreme position forming an acute angle with the toe portion of the foot whereby when the swimmer is in a horizontal position in the water and swings his legs up and down each fin will have a forward propelling effect both during the upward and the downward movement of the corresponding leg. 70 75 80 85

2. A swinging appliance comprising a fin having a relatively stiff body and a flexible tip, means for attaching the fin to the bottom of the foot of a swimmer to swing below the foot about an axis extending transversely to the foot, and means to limit the swinging movement so that in each extreme position said fin stands at an angle to the plane of the bottom of the foot, said fin in one extreme position forming an acute angle with the heel portion of the foot and in the other extreme position forming an acute angle with the toe portion of the foot whereby when the swimmer is in a horizontal position in the water and swings his legs up and down each fin will have a forward propelling effect both during the upward and the downward movement of the corresponding leg. 90 95 100

In testimony whereof, I have signed my name to this specification.

LE ROY FLETCHER SNAPP.
